UNITED STATES PATENT OFFICE.

GEORGE HOWLETT DAVIS, OF WEST ORANGE, NEW JERSEY.

COMBINED ELECTRICAL PIANO PLAYING AND RECORDING ATTACHMENT.

No. 923,147.

Specification of Letters Patent.

Patented June 1, 1909.

Application filed November 26, 1901. Serial No. 83,687.

To all whom it may concern:

Be it known that I, GEORGE HOWLETT DAVIS, a citizen of the United States, residing at West Orange, in the county of Essex and State of New Jersey, have invented new and useful Improvements in Combined Electrical Piano Playing and Recording Attachments, of which the following is a specification.

- 10 This invention relates to a combined electrical playing and recording attachment for pianos, and has for some of its objects, first; to provide an electrical piano-playing attachment that may be readily transformed 15 into a device for automatically recording music manually performed upon the piano, and vice versa; second; to provide means for throwing the key-actuating means out of action when the attachment is converted into 20 a music recorder; third; to provide means for counterbalancing the friction shoes; fourth; to provide means for positively holding the friction shoes out of action and out of contact with their propelling means 25 when the mechanism is used as a recorder solely; fifth; to provide a rest-rail or support for the friction shoes when the latter are thrown into contact with their propelling means during the playing operation.
- 30 The invention also has for its object to provide certain other improvements in the construction and arrangement of various details of the apparatus which will fully hereinafter appear.
- 35 To these ends my invention consists in the features and in the construction, combination and arrangement of parts hereinafter described and particularly pointed out in the claims, reference being had to the accompanying drawings forming a part of this specification, wherein—

Figure 1 is an end elevation of a piano keyboard showing my attachment applied thereto, some of the parts being shown in section 45 and others broken away to avoid confusion in the showing. Fig. 2 is a view in front elevation thereof, some of the parts being omitted to avoid confusion in the showing. Fig. 3 is a detail view of one of the shoes. Fig. 4 is a diagrammatic view illustrating the 50 electric circuits. Fig. 5 is a longitudinal view of the music sheet holder, showing the roll-holder partially drawn out. Fig. 6 is a vertical sectional view taken on the line 6—6 55 of Fig. 5. Fig. 7 is a bottom plan view of the music sheet holder. Fig. 8 is an end view of

the same, portions being shown in section. Fig. 9 is a detail view of the frame carrying the contact roller. Fig. 10 is a detail view illustrating the manner of journaling the delivery roller. Fig. 11 is a detail view of roll carrier extension latch. Fig. 12 is a side view of the music sheet holder, showing the mechanism for varying the speed at which the music sheet is driven. Fig. 13 is a detail view showing the gearing connected to the take-up roller. Fig. 14 is a detail sectional view of the switch-bar and the coacting contacts.

Before proceeding to describe the construction of my improved attachment I will explain that it relates to that class of piano playing attachments wherein a perforated music sheet is caused to travel over a metallic roller which forms part of an electric circuit, 70 a series of metallic fingers or brushes, termed "selectors" resting on the music sheet at the point where it passes over the contact roller. Said selectors are equal in number to the piano keys and a conducting wire leads from each selector to an electro-magnet, there being one electro-magnet for each piano key. Each of said magnets controls mechanism 75 for actuating its corresponding piano key, the construction of which is such that when any particular magnet is energized it puts in 80 operation the corresponding actuating mechanism and operates its piano key to sound a note. Conducting wires lead from each electro-magnet to a battery or other electric 85 generator and from the latter a conducting wire-leads to the contact roller. It follows, therefore, that as long as an imperforate portion of the music sheet lies between the selectors and the contact roller the circuits will 90 be broken by the music sheet and none of the piano keys will be actuated. Whenever a 95 perforated portion of the music sheet, however, comes between the end of any one of the selectors and the contact roller said selector will immediately spring into contact with said roller and close the circuit through a corresponding magnet and actuate a corresponding piano key. This broad principle 100 of operation is common to all the several 105 self-playing musical instruments hereinbefore referred to, and is only briefly outlined herein to enable the present invention to be more readily understood.

Referring to the drawings the numeral 1 110 indicates a drum one end of which is journaled in one of a pair of metallic hangers or

brackets 2, pendent from a wooden base 3 secured to the underside of the keyboard 4 of a piano, and the other end of said drum is journaled in a ball bearing 5 supported by the 5 motor frame, as will more fully hereinafter appear. The hangers 2 are rigidly united by an angle-iron or bar 6 L shaped in cross-section, said hangers and angle iron forming a frame which supports all the parts forming 10 the action for operating the piano keys, as contradistinguished from the music sheet holder and its connected parts. Supported on the angle-iron 6 is a series of electro-magnets 7, equal at least in number to the piano 15 keys, and in some cases slightly exceeding in number the number of the piano keys. The magnets 7 rest on the horizontal web of the angle iron 6, as most clearly shown in Fig. 1 of the drawings and are rigidly secured to and insulated therefrom in any suitable manner.

Adjustably screwed or bolted to the vertical web of the angle iron 6 are a number of flat springs 8, one being disposed opposite 20 each magnet, and each of which is bent at its upper end horizontally over the corresponding magnet. Passing through the free horizontal end of each spring 8 is the upper threaded end of a rod 9, preferably of brass, 25 on the upper end of which is screwed a nut, and fixed on said rod immediately beneath the spring is an armature 10. The rod 9 extends down between the two spools of the magnet and loosely projects through a suitable perforation formed in the horizontal web 30 of the angle iron 6 which acts as a guide for said rod. To the lower threaded end of the rod 9, is secured by means of a set-screw a block 11 (see Fig. 3) to which is pivoted, as at 12, one of 40 the upper corners of a shoe 13. The lower end of the shoe is slightly convex, as shown, and normally lies slightly above the drum 1. Screwed on the rod 9 between the upper end 45 of the block 11 and angle iron are two jam-nuts 14, and resting on the uppermost of said nuts is a disk 15 of felt or similar yielding material. By means of the jam-nuts the position of the shoe relatively to the drum may be accurately and finely adjusted. The 50 felt disk or washer operates to render the jam-nuts noiseless when they strike the underside of the angle iron when released by the magnet as hereinafter described. To the other upper corner of the shoe 13 is pivoted the lower end of a vertically movable striker-rod 16, the upper end of which loosely 55 passes through a suitable guide 17 and is adapted, when raised, to strike the underside of the inner or rear end of a piano key 18 immediately above it, or a projection 19 on said key. The drum 1 is continuously rotated in the direction indicated by the arrow in Fig. 1, by the means hereinafter described, and whenever one of the magnets is energized it attracts its armature 10, thereby

depressing the rod 9 carried by it, and forces the curved lower edge of the shoe 13 into contact with the drum 1. Owing to the rotation of the drum the shoe is rocked about the pivot 12 as a center, thereby thrusting the 70 striker-rod 16 upward against the end of the corresponding piano key 18 and causing the latter to sound a note.

In rear of the drum 1, and parallel therewith, is arranged a rest-rail 19^a, upon which 75 the friction shoes 13 may be brought to rest and upon which they are supported after having been kicked off the rotary drum through engagement therewith, the shoes being thus supported as long as the armature is held to its magnet poles. The rest-rail may be supported in any suitable manner from a part of the attachment. When the shoes are brought into contact with the rotary drum they are instantly thrust or 80 kicked rearwardly as shown in dotted lines, Fig. 3, and in the case of a sustained note, for instance, unless some means is provided to support and hold the shoes when in their active position, away from and clear of the 85 drum, they are liable to fall back into contact with, and cause a frictional drag upon the drum, requiring more power to drive the latter and resulting in more or less wear to the shoe-faces and drum, all of which is 90 objectionable. The rest-rail thus not only serves as a stop to prevent the shoes from being thrown back into contact with the drum, but also saves wear on the shoes and a waste of power when the shoes rest on the 95 drum during any considerable time, as, for example, when a sustained note is being played.

For a purpose hereinafter to be explained a front rest-rail 19^b is provided, said rail 105 being made movable toward and from the shoes by movably arranging its ends in guides 20 formed on the lower ends of brackets 21 pendent from the angle-iron 6, and by pivotally attaching to each end 110 thereof a lever 22 said levers being pivoted intermediate their ends to said brackets, one of said levers and brackets being clearly shown in Fig. 3. A rail 23 is also arranged in front of the shoes and is supported by 115 hangers 24 pendent from the angle iron 6, said rail serving as a support against which the shoes rest when out of action and preventing the shoes from swinging too far away from the drum. To the lower front edge or toe of 120 each shoe is attached a counterbalance, consisting of a threaded pin 25 fixed in the shoe and having screwed thereon a weight 26. By adjusting the weight on the pin the shoe can be nicely counterpoised so as to counterbalance the weight of the striker-rod 16, and render it light and quick in action.

For rotating the drum 1 I employ an electric motor 27 (see Figs. 1 and 2) the commutator 28 of which is arranged inside the field 130

pieces 29, which effects an economy in space and permits the employment of a special form of brush-holder, the numeral 30 indicating the brushes and 31 the holder or 5 brush-heads, which are mounted on threaded rods 32 adjustably fixed in bracket-arms 33 (preferably of brass) bolted to the field pieces. The boxing of the ball bearing 5 is seated in a recess formed in the field core 34, 10 thus dispensing with a special or separate seat therefor. The bracket or hanger 2 supporting the motor is preferably of brass and has the angle iron 6 secured thereto by machine screws 35. Two binding posts 36 and 15 37 see Fig. 2 are also secured to the brass hanger 2, and the latter in turn is secured to the base 3 of the key board 4 by lag-screws 38. The motor 27 is secured to the hanger 2 by two machine screws 38^a.

20 An electro-mechanical governor 39 is rigidly secured to the underside of the motor by a frame 41, consisting of an iron strap secured to the underside of the motor by screws 42, thence bent downward into substantially 25 semi-circular shape, thence extending vertically, and at the upper end of the vertical portion is bent horizontally, as shown in Fig. 2. In the free end of the frame 41 and in the lowest portion thereof respectively are 30 mounted journal pins 43 and 44, between which is journaled the vertical governor-shaft 45, having mounted thereon a sliding collar 46, adapted to be raised and lowered in a well known manner by the centrifugal action 35 of weights or balls 47 mounted on blade-springs 48 attached at their opposite ends to the collar 46 and the lower end of the governor-shaft respectively. In adjustable contact with the collar 46 is a metallic brush 49, 40 held in a brush-holder 50, which is rotatably mounted in a bearing-block 51 of insulating material 52, fixed to the frame 41. To said brush-holder is fixed one end of a crank-arm 53, the other end of which is pivotally connected to one end of a link 54, and the other 45 end of said link is pivoted to one arm of a bell-crank lever 55. To the other arm of said bell-crank lever is pivoted one end of a link 56, the opposite end of which is pivoted 50 to one arm of a bell-crank lever 57 (see Fig. 4). To the other arm of the bell-crank lever 57 is pivoted one end of a link 58, the opposite end of which is in like manner connected to an expression lever 59 to be hereinafter 55 described. In Fig. 1, the end of the link 58 that connects with the bell-crank 57, is broken away to avoid confusion in the showing, the complete connection of these parts being illustrated in Fig. 4. By oscillating the expression lever it will be manifest that through the medium of the connections described the brush-holder 50 will be rocked in its bearing and the brush 49 will be moved toward and from the sliding collar 46.

60 To the brush 49 is attached, one end of a

wire conductor 60, the other end of which is connected to a contact presently to be described, and to the frame 41, which is insulated from the motor is attached the end of a wire 61, which is in series with the motor, 70 as most clearly shown in Fig. 4 and as both wires 60 and 61 form part of an electric circuit, as will hereinafter be described, both the governor and motor are in series, it therefore follows, that whenever the speed of the 75 motor becomes such as to cause the governor to move the collar 46 away from the brush 49 the circuit will be broken and the motor will cease to be driven. The circuit will remain broken until the speed of the motor 80 again becomes normal when the governor will close the circuit between the collar 46 and brush 47. In this manner the speed of the motor, and hence the speed of rotation of the drum 1, will be automatically maintained 85 constant. By turning the expression lever 59, as before described, the brush 49 can be adjusted toward and from the sliding collar 46, and hence the speed of the motor and drum can be regulated at will. In 90 order to drive the governor at a speed proportionate to the speed of the motor, a collar 62, preferably faced with leather, is fixed on the governor-shaft 45, and is in frictional contact with an annular rim 63 fixed to the 95 motor armature 64. It will be readily seen, that by the means described the governor will be driven at a speed exactly proportionate to, but much greater, than the motor. The wire 60 is connected by a branch 65 with a 100 battery or generator 66, and from said generator leads a wire 67 that is connected to the expression lever 59. Said expression lever is arranged in movable engagement with a 105 segment shaped contact 68 to which is connected the wire 61 after it leaves the motor. The circuit is traced from the generator 66 (see Fig. 4) by wires 65 and 60, through the brush 49, sliding collar 46, governor-shaft 45, frame 41 and wire 61 to and through the motor 110 and from the latter to the contact 68, thence through lever 59 and wire 67 back to the generator. It will be evident that if the expression lever 59 be moved to the position marked "Off" in Fig. 4, it will be thrown out of engagement with the contact 68 and the circuit will be broken, thus throwing the motor 115 out of action.

120 My improved music holder comprises two horizontally sliding frames movable together and independently of one another and both supported by a fixed frame secured to the underside of the base 3 of the piano keyboard, said music holder being constructed as follows, reference being had to Figs. 5, 6, 7 and 8. The numeral 69 indicates a flat rectangular and open metallic frame secured to the underside of the base 3 in any suitable manner and having opposite 125 parallel depending sides 70 provided with

outwardly and horizontally extending flanges 71. The music holder proper comprises an upper and a lower rectangular open metallic frame respectively indicated 5 by the numerals 72 and 73, the sides of the frame 72 being provided with internal longitudinal grooves 74 into which the flanges 71 loosely project, said flanges forming ways on which the frame 72 may be slid in and 10 out beneath the keyboard of the piano. For the convenience of description I term the frame 72 the "selector frame." Mounted between the sides of the frame 72 is a transverse bar 75 in which are fixed the 15 selectors 76 each consisting of a metallic brush, the brushes being insulated from the selector-bar 75 and from each other, there being at least as many selectors as there are piano keys. The opposite lower edges 20 of the sides of the selector frame 72 are provided with inwardly and horizontally projecting flanges 77 which loosely project into corresponding grooves 78 formed in the upper outer portions of the sides of the frame 73 which I term the "roll-holder frame." The roll-holder frame may be 25 freely slid back and forth on the flanges 77, or both the selector and roll-holder frames may be slid in and out together on the 30 flanges 71 of the fixed frame 69.

Journaled in the frame 73, in the manner hereinafter described, is a delivery roller 79 and a take-up roller 80, the delivery roller being the roller on which the perforated 35 music sheet 81 is wound and the take-up roller operating to unwind the music sheet from the delivery roller. Pivoted, as at 82, to lugs 83 formed on the outer ends of the opposite sides of the roll-holder frame 73, are 40 two arms 84, united at their inner ends by a cross-bar 85, preferably formed integral with said arms. Journaled in bearings 86 formed on the inner ends of the arms 84 is the contact roller 87, consisting of a metallic roller 45 or metal covered roller, over which the music sheet passes as it is unwound from the delivery roller onto the take-up roller, as most clearly shown in Fig. 5. A coiled spring 88 is arranged between the underside of the 50 cross-bar 85 and a transverse integral web 89 uniting the two sides of the roll-holder frame, and operates to normally hold the contact-roller in engagement with the ends of the selectors. On the outer or free ends of 55 the arms 84 are formed outwardly and horizontally projecting lugs or projections 90 which are adapted to engage the upper sides of the flanges 77 of the selector frame 72. As shown by dotted lines in Fig. 5, the outer 60 ends of the flanges 77 are beveled, as at 91, and have formed in their upper sides immediately in rear of said beveled portions grooves or recesses 92, in which the lugs 90 rest when the two frames 72 and 73 are closed 65 together. Pivoted to the inner end portion

of each of the arms 84 is one end of a link 93, the other end of which is pivoted to one end of a bell-crank lever or trigger 94, pivoted, as at 95, to the side of the roll-holder frame. The free or depending end 96 of the lever projects 70 below the roll-holder frame and is formed to be conveniently engaged by a finger of the hand to draw out the roll-holder frame. When the operator engages said trigger-levers to draw out the roll-holder 75 frame the pressure on said levers first rocks them on their pivots 95, and through the medium of the links 93 depresses the inner ends of the arms 84, and the roller 87, thereby lifting the lugs 90 out of the grooves or recesses 80 92, whereupon the roll-holder frame is released from the selector frame and may be freely drawn out. This movement also lowers the contact-roller 87, away from the 85 selectors 76, so that there is not any danger of said selectors catching in the perforations of the music sheet and being thereby broken, bent, or otherwise injured. When the roll-holder frame is pushed back into place beneath the selector frame the lugs 90 ride up 90 the inclined ends 91 of the flanges, thereby lowering the contact-roller until said lugs settle into the grooves or recesses 92, upon which the spring 88 raises the roller into contact with the selectors and holds the lugs 95 seated in said grooves, thus locking the roll-holder and selector frames together.

Each of the selectors 76 is electrically connected to one of the electro-magnets 7 as follows. Attached to the base 3 of the keyboard of the piano is a bar 97, preferably of insulating material, provided on its underside with a plurality of contacts 98, equal in number to the selectors, (see Figs. 1, 4 and 14) and attached to the underside of said base 3, and projecting rearwardly therefrom beneath the contacts 88, is an equal number of spring contacts 99. A wire 100 connects each contact 98 with an electro-magnet 7, and each magnet is connected to one of the 105 selectors by a wire 100^a and each spring contact 99 is connected to an end 60^a of the wire 60 before described. A wire 101 leads from the contact roller 87 and is connected to the 110 wire 61.

The numeral 102 indicates a bar of insulating material provided on its underside with a series of contacts 103 the forward ends of which project beyond the front edge of said bar and form spring contacts. A 120 series of contacts 104 are fixed to the upper sides of the bar 102, the opposite ends of said contacts being free and forming spring contacts. Each series of contacts 103 and 104 is equal in number to the series of contacts 98 and 99. The bar 102 is fixed in any suitable manner so that each contact 104 will engage a contact 98, and each contact 103 will in like manner engage a contact 99. This arrangement greatly facilitates and 125 130

lessens the labor of assembling and connecting up the parts, as all the contacts can be simultaneously connected up by merely slipping and fixing the bar in place. The 5 bar 102 may conveniently be secured in place by fixing dowel pins 105 in the bar and inserting said dowel pins in suitable sockets or mortises formed in the base 3. The contacts 103 and 104 Fig. 14 are thrown 10 into and out of electrical contact to short circuit the key contacts 157, and 158 presently to be described by a switch-bar consisting of a bar 106, preferably wedge-shaped in cross-section, which may conveniently be formed of wood and provided 15 with a metallic contact clip 107, which may be brought into and out of contact with the tongues, 103 and 104 and electrically connect same in circuit with the magnets 7 and key 20 contacts 157 and 158, as hereinafter described. Dowel pins 108 are fixed in said bar and are movably fitted in sockets or mortises 109 formed in the bar 102. Coiled springs 110 are arranged between the adjacent faces of the bars 102 and 106 and operate to separate them. Projecting from the ends of the bar 102 are lugs 111 to which are pivoted cams 112 having hand-levers 113. When the levers 113 of the cams are thrown 30 up into the position shown in Fig. 1 the springs 110 will force the switch-bar 102 from between the contacts 103 and 104 and the latter will be electrically disconnected; but if the levers 113 be thrown down into the 35 position shown in Fig. 14 the cams will force the switch-bar between the contacts 103 and 104 thereby connecting the contacts 98 with the contacts 99.

Let it be assumed that the switch-bar 106 40 is in the position last above described and that the expression lever 59 has been turned to throw the motor into circuit. Let it also be assumed that the music sheet 81 is being unwound from the delivery roller 79 by the 45 take-up roller 80 by means which will presently be described. Then as a perforated part of the music sheet passes beneath any one of the selectors 76 a circuit will be closed through a corresponding magnet 7, as follows. Starting from the selector thus brought into contact with the contact-roller 50 the circuit is traced from the latter by wire 101 to the wire 61, thence through the contact 68 and expression lever 59, thence by wire 67 to the generator 66, from the latter by wires 65 and 60^a to one of the contacts 99, thence through contact 103, switch-bar 106 and contact 104 to contact 98, thence by wire 100 to one of the magnets 7 and from the latter back to the selector by wire 100^a. The magnet thus energized throws a corresponding shoe 13 into engagement with the drum and causes the striker-rod 16 connected thereto to actuate a key 18. Each 60 piano key is thus actuated at the proper

moment to sound a note, as determined by the location of the perforations or slots in the music sheet 81, the duration of the note being dependent upon the length of the slot in the music sheet. By turning the expression 70 lever in the proper direction the motor can be caused to run faster or slower, in the manner before described, hence the force with which any key or set of keys is struck can be regulated. In practice the music sheet is 75 marked at the proper points to indicate when the notes are to be played loud or soft and therefore by watching the music sheet as it passes from the delivery roller to the contact roller and turning the expression lever in 80 the proper direction at the proper intervals the operator can cause the attachment to execute the composition with the proper expression. It is for this purpose that I arrange the selector and music-roll holder 85 frames in the manner described, so that by drawing them out from beneath the keyboard the music sheet is in plain view of the operator and enables him to properly control or manipulate the expression lever, and when 90 the attachment is not in use said frames can be pushed back beneath the keyboard where they will not interfere with a performer using the piano in the usual or ordinary manner. 95

In order to cause the music sheet to travel over the contact roller at any desired speed I provide the following means. Referring to Figs. 1 and 2, the numeral 114 indicates a shaft journaled between suitable journal pins 115 and 116 and having fixed thereon a pulley 117, which is driven by a belt 118 from a pulley 119 on the drum 1. Movable mounted on, but incapable of rotating independently thereof, is a relatively large 100 friction disk 120, which is held in frictional engagement with a smaller friction wheel 121 by a coiled spring 122 arranged on the shaft 114 and bearing against a collar 123 on said shaft. As shown the periphery of the friction wheel 121 bears against the face of the disk 120, and said friction wheel is fixed on a shaft 124, which is longitudinally movable in a bearing formed in a bracket 125 pendent from the underside of the base 3, and in a worm 126 which is rotatably mounted in a bracket 127 fixed to one side of the selector frame 72, said worm being splined on the shaft 124 so that it can slide thereon but not rotate independently thereof. The worm 110 126 gears with a worm wheel 128 (see Figs. 12 and 13) journaled in one end of a swinging arm 129, the other end of said arm being pivoted on the journal of the take-up roller 80. Fixed on the journal of the worm wheel 128 115 is a pinion 130 which gears with a gear wheel 131 fixed on the end of the take-up roller 80 and thus rotates the latter to wind up thereon the music sheet 81. By mounting the 120 worm wheel in the end of the swinging arm 125 130

in the manner described the former is permitted to raise and lower slightly when engaging and disengaging the worm, which it must do whenever the roll-holder frame 73 is moved in and out independently of the selector frame 72. A pin 155 is fixed in one side of the roll-holder frame and acts as a stop or support for the swinging arm when said frame is drawn out. Fixed to or formed on the outer edge of one side of the selector frame 72 is a circular graduated dial or disk 132, pivoted centrally to the underside of which is one end of a lever 133, termed by me a "tempo-lever," said lever being provided at its outer end with a handle 134 (see Fig. 8) and with a pointer 135 which overhangs the graduations on the disk or dial. Pivoted to the tempo-lever is one end of a slotted bar 136, the other end of which is pivoted to the outer end of a lever 137, the inner end of which has fixed thereon a pinion 138 (see Fig. 7) and is pivoted to a bracket arm 139 fixed to one side of the selector frame 72. The inner end of the tempo-lever in like manner has fixed thereon a similar pinion 140, and both said pinions gear with a rack-bar 141 that is movably supported longitudinally by headed pins 142 and 143 which project from the undersides of the bracket-arm 139 and disk 132 respectively and extend through slots 144 formed in the ends of said rack-bar. Pivoted to a bracket-arm 145 fixed to the frame 69 is a bell-crank lever 146, the end of one arm of which is provided with a headed pin 147 which projects through the slot 148 in the slotted bar 136, and pivoted to the end of the other arm of said bell-crank lever is one end of a rod 149, the other end of which is hooked into a loop 150 formed centrally in a rod 151 which is pivotally connected at its upper end to an eye 152 on the rear end of the frame 69 and at its other end is loosely looped, as at 153 about a peripherally grooved collar 154 fixed by a set screw on the shaft 124.

The operation of this part of the device is as follows: Let it be assumed that the parts are in the position shown in Fig. 7, wherein the selector and roll-holder frames are shown 50 pushed in beneath the keyboard, and in which position the take-up roll will be driven at its fastest speed. Now if the lever 133 be swung about its pivot in the direction of the arrow it will draw forward with it and 55 at the same time move the slotted bar 136 toward the music holder or toward the left as viewed in the drawing. This movement of the slotted bar rocks the bell-crank lever 146 on its pivot and thrusts rearward the 60 rod or link 149, thereby swinging the lever 151 rearward and moving the shaft 124 in the same direction, thus shifting the friction wheel nearer to the center of the friction disk 120, and consequently reducing the speed of 65 rotation of the shaft 124. The shaft 124

being geared to the take-up roller through the gearing described, said roller will also, therefore, be driven at a slower speed and cause the music sheet to travel over the contact roller at a correspondingly slower speed. 70 By gearing the slotted bar 136 to the rack-bar 141 in the manner described said slotted bar will always remain parallel with the adjacent side of the music holder and hence a given movement of the tempo-lever will 75 impart a corresponding movement to the bell-crank lever 146 irrespective of the position of the tempo-lever. By connecting the tempo-lever to the bell-crank lever 146 by means of the slotted bar 136, as described, 80 the selector frame 72 may be freely moved in and out without in any manner affecting the position of the friction wheel 121 relatively to the friction disk 120, and said friction wheel may be moved toward and from 85 the center of the friction disk to regulate the speed of travel of the music sheet irrespective of the position the selector frame may be in, whether it be entirely pushed in or drawn out or at any intermediate point. I have 90 described the tempo-lever as being pivoted centrally to the underside of a graduated disk fixed to or formed with the outer end of one side of the selector frame. A similar graduated dial or disk 156 is arranged on the 95 opposite side of said selector frame and pivoted centrally to the underside thereof is the expression lever 59, the segment-shaped contact 68 being also fixed to the underside of said disk 156. By moving the expression 100 lever to register with the different graduations on the dial the speed of the motor will be correspondingly adjusted through the medium of the connections and governor in the manner before described. 105

As above described the attachment is arranged for automatically playing on the piano any composition that perforations or slots in the music sheet may determine. I will now describe the means by which the instrument is transformed into an apparatus for recording upon an imperforate sheet any composition which may be played upon the piano by a performer in the usual manner. For this purpose I employ an imperforate 110 music sheet consisting of a sheet of paper of the same size as the perforated music sheet, but made of paper having fine metallic particles evenly and thickly distributed through it and incorporated therein during the course 115 of the manufacture of the paper. This paper in practice is made sufficiently thin to permit the minute metallic particles to protrude on opposite sides of the paper so as to be exposed. An imperforate sheet of such paper is to be used in lieu of the perforated sheet of Manila paper employed when the attachment is used as a self-playing attachment. 120

Referring to Figs. 1 and 4 of the drawings, 123

the numerals 157 and 158 respectively indicate two metallic spring contacts attached to the piano keyboard underneath the outer end of each piano key 18, said contacts being 5 normally separated. To the contact 157 is connected one end of a wire 159, the other end of which is connected to one of the contacts 104, and in like manner the other contact 158 is connected by a wire 160 to a corresponding contact 103, it being understood that each pair of contacts under each key of the piano is in the same manner connected to a pair of contacts 103 and 104. To convert the piano playing attachment into an attachment for recording the music played on the piano manually the handles 113 of the cams 112 are thrown up into the position shown in Fig. 1, whereupon the springs 110 force the switch-bar 106 from between and out of engagement with the contacts 103 and 104, thereby breaking the circuit between said contacts. Then by depressing the levers 22 the bar 19 is raised until it bears against the undersides of all the shoes 13, thereby throwing the latter out of action. A delivery roll wound with the metallized imperforate music sheet is then placed in the roll-holder frame, passed over the contact roller and attached to the take-up roller in the same manner as 30 the perforated music sheet, and the tempo-lever set to give the desired speed to the sheet feeding mechanism. The expression lever is now turned until it engages the contact 68, thus putting the motor in circuit, and said expression lever is then adjusted to give the desired speed to the motor. The performer then plays upon the piano in the usual manner. As each key is depressed it presses together the contacts 157 and 158 underneath 40 it, thus closing the circuit at that point, which is traced as follows, reference being had to Fig. 4. Starting from the generator 66 the circuit is traced over the wires 65 and 60^a, through the contacts 99 and 103 to the wire 160, over said wire to and through the contacts 158 and 157, thence by wire 159 to contacts 104 and 98 to wire 100, then through one of the electromagnets 7 and by wire 100^a to one of the selectors 76. As before described the metallized sheet is traveling between the selectors and contact roller 87 and in contact with both of them, hence the metallic particles incorporated in said sheet place said selectors and contact roller in electrical contact. Therefore the circuit continues from the end of the selector through the metallized sheet to the contact roller 87, over the wire 101 to wire 61 and over the latter to contact 68, from the latter to the expression lever and thence by the wire to the generator 66, thus completing the circuit. As the current passes through the minute metallic particles passing between and in contact with the selector and contact roller, the resistance offered by said particles raises

them to a high heat, thereby scorching and discoloring the paper, and even sometimes causing the particles to drop from the sheet, but this in no way proves objectionable. The length of the mark or discoloration thus made on the paper will be dependent upon the duration of the note played and consequently the length of time the circuit remains closed, a short staccato note producing a mere dot, while a long sustained note will result in a correspondingly long mark or stripe. It will of course be understood that as each key is struck a corresponding selector will be thrown into circuit and the note will be recorded in the manner described on the metallized sheet. After the entire composition has been played, and has been thus recorded on the metallized sheet, the latter is removed from the music sheet holder and the recorded notes are cut out by hand with a punch, or by other suitable means. The sheet then becomes a music sheet, faithfully recording the music performed upon the piano, and is then coated with shellac, or other suitable material to insulate the metallic particles. The music sheet thus produced can then be wound upon a delivery roller and placed in the music holder, when by forcing the switch-bar between the contacts 98 and 99, lowering the bar 19 from beneath the shoes, and turning the expression lever to throw the motor into circuit, the piano will automatically play or repeat the composition previously manually played upon the piano. Or instead of coating the sheet with shellac or other insulating material to render it suitable for use as a music sheet, it may be employed as a pattern or stencil for reproducing duplicate music sheets indefinitely in a usual and well known manner.

By placing contacts similar to the contacts 157 and 158 under each foot pedal of the piano, providing corresponding selectors, and connecting up said contacts and selectors in precisely the same manner as the piano keys, the action of the pedals can obviously also be automatically recorded in the same manner as that of the keys.

In order to readily remove the delivery roller from its frame so as to change from one music sheet to another, and in order to rewind the music sheet thereon, I journal the delivery roller in the frame in the manner, and provide rewinding mechanism, which I will now describe. A trunnion 161 is fixed on each end of the delivery roller 79 (see Figs. 8 and 10) and is provided with one or more laterally projecting lugs or wings 162. Journaled in each side of the roll-holder frame 73 is a spindle 163, provided at one end with a head 164 and having a central socket in which the trunnion 161 is adapted to be loosely fitted, and also having a slot or recess 165 for the reception of the lug 162, whereby the delivery roller and said spindle are caused

to rotate together. The spindle adjacent to the head 164 is provided with an integral collar or enlargement 166 that is adapted to fit within a corresponding socket 167 formed 5 in the inner side of the frame 73. Splined on the spindle 167 is a pinion 168 that is disposed in a recess 169 formed in the frame 73. Pivoted to the frame 73, before referred to, is a hooked catch 170, Fig. 11, the forked end 10 171 of which is adapted to hook over the collar or enlargement 166, as hereinafter explained. On one side the frame 73 is provided with an open bearing 172. To journal the delivery roller in place one of the trunnions 161 is inserted in the socket in the end 15 of the spindle 163 and the opposite trunnion is dropped into the open bearing 172. There are two sizes of music roll holders on sale on the market and the shorter rolls are too short 20 to be journaled in the manner described. When such rollers are to be used the spindle is drawn out, as shown in Fig. 10, and the hooked catch is swung up or over so as to hook over the spindle behind the head 164, 25 thus holding the spindle in place to be engaged by the trunnion of the shorter roller. Knobs 173 are fixed on the end of the roll-holder frame to furnish convenient means for drawing out both said frame and the selector 30 frame from beneath the keyboard. Journaled on a stud-shaft on one side of the frame 73 is a pinion 174, see Fig. 12, which gears with the pinion 168 before described, and also journaled on a stud-shaft on the same side of 35 said frame is a gear wheel 175 which gears with the pinion 174. A crank or handle 176 is fixed to the gear wheel 175. After the music sheet has been unwound from the delivery roller it may be re-wound thereon by 40 turning the gear wheel 175 by its handle 176, whereby, through the gearing described the music sheet may be rapidly rewound onto the delivery roller. By unhooking the end of 45 the music sheet from the take-up roller the delivery roller may be removed from the frame and another one inserted.

In the foregoing description, and in the appended claims, I have used the term "perforated music sheet," such being the term by 50 which such sheets, when employed for controlling self-playing musical instruments, are well known, and by such term is understood a strip of paper, or other suitable flexible material, provided with slits or slots of varying 55 lengths, the location and length of the slits corresponding to the different notes and their duration. Hence, I wish it to be understood that wherever the term "perforated music sheet" is employed, a sheet having slits or 60 slots is meant, the said term being employed in its conventional sense as well understood in the art.

While I have shown and described the attachment applied to a piano, it may obviously 65 be applied to other keyed musical in-

struments, and in the claims hereinafter following wherever the term "piano" is employed I wish to be understood as including keyed musical instruments of every kind to which the attachment is or may be applicable. 70

I do not claim herein the music roll holder shown and described, as this is claimed in my divisional patent No. 854,689, dated May 21, 1907. 75

Having described my invention, what I claim is—

1. In an attachment for musical instruments, the combination with mechanism for automatically playing said instrument and for producing electrically upon an imperforate sheet a record of music played manually on the instrument, means for throwing the playing portion of the mechanism out of operation and means for rendering the recording mechanism inoperative, a part of said recording portion coöperating with a perforated music sheet for controlling the playing portion. 80

2. In an attachment for musical instruments, the combination with mechanism for automatically playing said instrument and for producing electrically upon an imperforate sheet a record of music played manually on the instrument, means for throwing the recording portion of the mechanism out of 85 operation, and means for rendering the playing portion operative, a part of said recording portion coöperating with a perforated music sheet for controlling the playing portion. 90

3. In an attachment for musical instruments, the combination with mechanism for automatically playing said instrument and for producing electrically upon an imperforate sheet a record of music played manually on the instrument, means for rendering either the playing portion or the recording portion operative, and means for throwing out of operation either the playing portion or the recording portion, a part of said recording portion coöperating with a perforated music sheet for controlling the playing portion. 105

4. In an attachment for musical instruments, the combination with mechanism for automatically playing said instrument and for producing electrically upon an imperforate sheet a record of music played manually on the instrument, said mechanism including electrical contact fingers, means for throwing the playing portion of the mechanism out of operation and means for rendering the recording portion inoperative, the said contact fingers coöperating with a perforated music sheet for controlling the playing portion. 115

5. In an organized instrument for automatically playing music and for obtaining on an imperforate sheet a visual record of music 120

- played manually on a musical instrument, the combination with a musical instrument, of means controlled by a perforated music sheet for automatically actuating the sound-producing devices thereof, a series of electric contact devices between which either the imperforate or the perforated music sheet may be caused to pass to obtain the visual record or to control the operation of the actuating means for the sound-producing devices, electric circuits in which said contact devices are included, a normally open circuit maker and breaker arranged beneath each key of the musical instrument, wires leading from the two members of each circuit maker and breaker to corresponding contact devices, and a switch for throwing the said wires and circuit makers and breakers in and out of circuit at will.
6. In a combined automatic music playing and music recording apparatus, the combination with a musical instrument, of means for automatically actuating the sound producing devices thereof, a series of electric contact devices between which either an imperforate sheet or a perforated music sheet may be caused to pass to obtain a visual record or control the operation of the actuating means for the sound producing devices, an electric circuit in which said contact devices are included, normally open circuit makers and breakers arranged to be operated by the keys of the musical instrument, wires leading from said circuit makers and breakers to corresponding contact devices, two separated contacts forming the terminals of each of said wires, and a switch bar adapted to bridge the said separated contacts of all the circuits, as and for the purpose specified.
7. In an organized instrument, electrically operated mechanism for automatically playing a musical instrument through the medium of a perforated music sheet, including means for producing upon an imperforate sheet a visual record of music played manually upon the instrument, said means consisting of electrical contact-fingers forming a part of the music playing mechanism.
8. In an organized instrument, electrically operated mechanism for automatically playing a musical instrument through the medium of a perforated music sheet, including means for producing upon an imperforate sheet a visual record of music played manually upon the instrument, said means consisting of electrical contact-fingers forming a part of the music-playing mechanism, and means for feeding the sheet between said fingers during the playing of the instrument.
9. In a piano attachment, the combination with electrically-operated mechanism for playing the piano, and electric means controlled by a perforated music sheet for controlling the action of the playing mechanism and for marking on an imperforate sheet the notes played manually on the piano, of means for holding a portion of the playing mechanism inactive during the marking operation.
10. In a piano attachment, the combination with electrically operated playing mechanism controlled by a perforated music sheet for playing the piano, of electric means controlled by the keys of the piano for marking on an imperforate sheet the notes played manually on the piano and for controlling the operation of the playing mechanism through the perforated sheet, and means for feeding either the perforated sheet or the sheet to be marked in associated relation with said electric means, substantially as described.
11. A piano having means controlled by a perforated music sheet for automatically actuating the piano keys to play the piano, said means including electric devices controlled by the piano keys when the piano is manually played for scorching an imperforate sheet where the latter is to be perforated to form a music sheet adapted to control the automatic playing mechanism.
12. In a piano playing attachment, the combination with means controlled by a perforated music sheet for actuating the piano keys to play the piano, including an electric circuit and selector fingers therein, circuit closers controlled by the operation of the piano-keys when the piano is played manually for completing the circuit through said selector fingers to burn an imperforate sheet and produce thereon a visual record of the music manually played, and means for holding the actuating means for the keys out of operation when the attachment is employed as a recorder.
13. The combination with mechanism controlled by a perforated music-sheet for automatically playing a musical instrument and for burning electrically upon an imperforate sheet a record of music played manually upon the instrument, means for throwing the playing portion of the mechanism out of operation, and means for rendering the recording portion inoperative, a part of said recording portion co-operating with a perforated music sheet for controlling the playing portion.
14. In a music playing attachment for musical instruments, the combination with means for actuating a sound producing device including a pivoted friction shoe, of a counter-weight attached to the shoe, for the purpose described.
15. In a music playing attachment for musical instruments, the combination with means for actuating a sound producing device including a pivoted friction shoe and a striker-rod connected thereto, of a counter-weight adjustably attached to the shoe and operating to counter-balance the weight of the striker-rod, substantially as described.
16. In a music playing attachment for mu-

sical instruments, the combination with means for actuating a sound producing device including a pivoted friction shoe and a striker rod arranged to be operated thereby, of a pin 5 fixed to said shoe, and a weight adjustably mounted on the pin and operating to counterbalance the weight of the striker rod, substantially as described.

17. In a music playing attachment for pianos, the combination with a drum and means for rotating it, of a series of electro-magnets, one for each piano key, an armature supported above each magnet, a rod pendent from each armature, a shoe pivotally 10 connected to the lower end of the rod and having a curved friction face arranged to be thrown into contact with the drum when the armature is attracted by its magnet, a striker-rod pivotally connected to the shoe and 15 adapted to strike the inner end of a piano key, and a counterweight attached to each shoe and operating to counterbalance the weight of the striker-rod, substantially as described.

18. In a music playing attachment for pianos, the combination with a drum and means for rotating it, of a series of electro-magnets, one for each piano key, an armature supported above each magnet, a rod pendent from each armature, a shoe pivotally 20 connected to the lower end of the rod and having a curved friction face arranged to be thrown into contact with the drum when the armature is attracted by its magnet, a striker-rod pivotally connected to one 25 side of the upper end of the shoe, and adapted to strike the inner end of a piano key, a pin fixed to the opposite side of the lower end of the shoe, and a weight adjustably mounted on said pin and operating to counterbalance 30 the weight of the striker-rod, substantially as described.

19. In a music playing attachment for musical instruments, the combination with a drum and means for rotating it, of a series 45 of electro magnets, an armature for each magnet, a rod pendent from each armature, a shoe pivoted to each rod, a striker-rod connected to each shoe and adapted to actuate a key of the musical instrument, and a rail ar- 50 ranged beneath the front end of all the shoes and operating to form a stop and support for the latter after being thrown into contact with the drum by the magnets, armatures and rods, substantially as described.

55 20. In a music playing attachment for pianos, the combination with a drum and means for rotating it, of a series of electro-magnets, one for each piano key, an armature supported above each magnet, a rod pendent 60 from each armature, a shoe pivotally connected to the lower end of the rod, a striker-rod pivotally connected to the shoe and adapted to strike the inner end of a piano key, and a rail arranged beneath one end of 65 all the shoes and operating to form a stop

and support for the latter after being thrown into contact with the drum by the magnets, armatures and rods, substantially as de- 70 scribed.

21. In a piano attachment, the combination with a contact roller and a plurality of selectors, one for each piano key, adapted to contact with the contact roller, electric circuits each including one of said selectors and the contact roller, a key striking mechanism, one for each selector, arranged to be put in operation to actuate a key when any one of said circuits is closed, whereby when any one of said selectors contacts with the contact roller a corresponding key will be 75 actuated, two separated contacts forming the terminals of each of said circuits, a movable switch bar adapted to bridge the said contacts of all the circuits, a normally open circuit maker and breaker arranged beneath 80 the end of each key, wires leading from the two members of each circuit maker-and-breaker to a corresponding pair of said terminal contacts, and means for moving said switch bar from between the terminal contacts to include said circuit makers-and-breakers in said circuits.

22. In a music playing attachment for musical instruments, the combination with a rotary drum, of a plurality of shoes arranged to be actuated by the drum, means for moving the shoes into contact with the drum, connections between the shoes and the sound producing devices of the musical instrument, and a rail arranged adjacent to the drum and 95 shoes and operating to form a stop and support for the shoes when the latter are thrown into contact with the drum during action.

23. In a music playing attachment for musical instruments, the combination with a 100 rotary drum, of a plurality of pivoted shoes arranged to be actuated by the drum, means for moving the shoes into contact with the drum, a connection between each shoe and a sound producing device of the musical instrument, and a rest-rail arranged beneath and in rear of the shoes and operating to form a 110 stop and support for the latter when thrown into contact with the drum during action.

24. In a piano attachment, the combination with key striking mechanism controlled by a perforated music sheet for automatically actuating the piano keys to play the piano, of means controlled by the piano keys when the piano is manually played for indicating on an imperforate sheet where the latter is to be perforated to form a music sheet adapted to control the automatic playing mechanism and cause the latter to automatically play on the piano the music previously played manually thereon, and means for locking the key striking mechanism against movement when the attachment is employed for preparing the imperforate sheet, substantially as described.

25. In a piano attachment, the combination with a rotary drum and means for rotating it, of a series of shoes, one for each piano key, arranged in proximity to the drum, 5 means for moving said shoes into contact with the drum, means actuated by the shoes for striking the piano keys, means controlled by the piano keys when the piano is manually played for indicating on an imperforate sheet 10 where the latter is to be perforated to form a music sheet adapted to control the automatic playing mechanism and cause the latter to automatically play on the piano the music previously played manually thereon, 15 a rail arranged beneath the shoes and means for raising said rail to hold said shoes against movement, substantially as described.

26. In music playing mechanism, the combination with a sound-producing device, of a 20 rotary element, a friction shoe co-operatively associated therewith and arranged to be actuated thereby, means operated by the

shoe for actuating the sound-producing device, and means for holding the shoe out of contact with the rotary element and in its 25 active position after it has been actuated by said element.

27. In music playing mechanism, the combination with a sound-producing device, of a rotary element, a friction shoe co-operatively associated therewith and arranged to be actuated thereby, means actuated by the shoe for operating the sound producing device, and means co-operating with the friction face of the shoe for engaging and holding the latter out of contact with the rotary element 30 after having been actuated thereby.

28. In testimony whereof I affix my signature in presence of two witnesses.

G. HOWLETT DAVIS.
